UNITED STATES PATENT OFFICE

143,530

DESIGN FOR AN APPLIQUE EMBLEM OR SIMILAR ARTICLE

William A. Giraldi, Davenport, Iowa, assignor to National Lock Company, Rockford, Ill., a corporation of Delaware

Application January 27, 1945, Serial No. 117,634

Term of patent 14 years

(Cl. D3—9)

To all whom it may concern:

Be it known that I, William A. Giraldi, a citizen of the United States, residing at Davenport, in the county of Scott and State of Iowa, have invented a new, original, and ornamental Design for an Applique Emblem or Similar Article, of which the following is a specification, reference being had to the accompanying drawing, forming part thereof.

In the drawing, the single figure of the drawing is a front elevational view slightly in perspective of an applique emblem or similar article
embodying my design.

I claim:

The ornamental design for an applique emblem or similar article, substantially as shown.

WILLIAM A. GIRALDI.
